UNITED STATES PATENT OFFICE.

NORMAN HORACE IZOD, OF SAMARAI, BRITISH NEW GUINEA, ASSIGNOR OF ONE-HALF
TO WILLIAM JACKSON, OF SAMARAI, BRITISH NEW GUINEA.

EXCAVATOR FOR FLESHING DIVIDED COCOANUTS.

1,356,527.

Specification of Letters Patent. Patented Oct. 26, 1920.

Application filed August 7, 1919. Serial No. 315,961.

To all whom it may concern:

Be it known that I, NORMAN HORACE IZOD, a subject of the King of Great Britain, residing at Samarai, in the Australian Territory of Papua, have invented a new and useful Improved Excavator for Fleshing Divided Cocoanuts, of which the following is a specification.

This invention refers to the removing of the meat or flesh from cocoa-nuts after such nuts have been split or divided and it has been specially devised in order to provide an excavator or excavating device or instrument whereby such meat or flesh (to afterward form copra) may be rapidly and thoroughly removed from the halved or divided cocoa-nuts.

This improved excavator for fleshing divided cocoa-nuts consists of one or more flexible knives or blades arcuated from a rotary support to a point or points the center of rotation and preferably slightly helically set at the leading or cutting edge and whose spheroidal curvature is adapted to be expanded by pressure upon the point or points and upon withdrawal of such pressure to recover normal position and to facilitate and control this expansion the point or points of the blade or blades is or are preferably affixed to a crown piece slidable on a stem in or about the driving shaft of the rear rotary support. But in order that this invention may be easily carried into effect the preferred practical adaption of same will now be described with reference to the drawings accompanying and forming part of this complete specification.

Figures 1 and 2 are longitudinal views at right angles to one another of this improved excavator for fleshing cocoa-nuts and Figs. 3, 4, and 5 are transverse sectional views of same at lines 3—3 4—4 and 5—5 respectively while Fig. 6 is an end view of the crown piece and Fig. 7 a similar view of the whole.

To a shaft 8 by means of a set screw 10 a head 11 is fastened in this case having three faces to each of which is affixed by screws 12 a flexible knife or blade 13. In the shaft 8 forwardly of the head 11 is a recess with clearance space 15 in which a spindle 18 is adapted to slide as far as control stud 16 in slot 17 in wall 9 of the recess of the shaft 8 will allow. On the outer reduced end of the spindle 18 is affixed say by a cotter pin the

crown piece 19 having wings 20 in a recess in each of which wings are fastened to it by rivets is the point of the blade 13 leaving a free leading or cutting edge 14 to said blade.

Each flexible blade 13 extends forwardly from the head 11 approximately parallel with the axial line of the shaft 8 and slightly helically set thereto and then spreading or rather curving as a sector of an approximate spheroidal wall inclining and terminating in a somewhat blind point at the center 14^a on an extension of said axial line where it is riveted to a wing 20 of the crown piece 19 as before mentioned.

The rotary head 11 being rotated by shaft 8 the outer ends of the curved blades represent a rotating approximately spheroidal cage with cutting edges on the sectors thereof (being the blades) and these cutting edges excavate or remove from the concave half cocoa-nuts placed over the junctioning ends of the blades the flesh or meat thereon or therein. Pressure is applied externally of the half-nut as the diameter thereof requires the crown piece spindle slides in recess of extension 9 of shaft 8 and the bodies of the flexible blades 13 spheroidically expand to said diameter and practically clear all the flesh from the half-nut wall as it is applied over and pushed against the outer end of the excavator and when the pressure is relieved the blades by their own elasticity slide the crown piece 19 outwardly and the blades take up normal position again.

What I claim as my invention, and desire to secure by Letters Patent is:—

1. In an excavator for fleshing divided cocoa-nuts a rotary flexible blade arcuate to the center of revolution and having its curvature expanded by pressure on its end.

2. An excavator for fleshing divided cocoa-nuts including a rotary head and a plurality of flexible pointed blades, carried by the head arcuate to a common center of revolution, and forming sector walls of a spheroidal cage adapted to be expanded on pressure being applied to the points of said blades.

3. An excavator for fleshing divided cocoa-nuts comprising a rotary head, a plurality of flexible blades forming sector walls of a spheroidal cage, and having their back ends carried by the head, and a crown piece holding the forward pointed ends of said

flexible blades, and with said head being arranged in an axial line and adapted to approach one another on pressure being applied to one of them.

5 4. In an excavator for fleshing divided cocoa-nuts, a rotary flexible blade having a cutting edge and arcuate and tapered to its center of revolution, and adapted to have its curvature expanded by pressure on its

10 outer end.

5. In an excavator for fleshing divided cocoa-nuts, the combination with a rotary shaft, of a head fixed on the shaft and a plurality of flexible blades fixed to the head

15 and having cutting edges and arcuate and tapered to their common center of revolution

tion and adapted to have their curvature expanded by pressure on their outer ends.

6. An excavator for fleshing divided cocoa-nuts as claimed in claim 5 wherein the 20 shaft is extended and provided with a recess, a stem slideable in the recess, and a crown piece fixed on the outer end of the stem, and having outer ends of the blades connected thereto.

25

In testimony whereof I have signed my name to this specification.

NORMAN HORACE IZOD.
